UNITED STATES PATENT OFFICE.

ORLANDO M. FRIEND AND SAMUEL E. FRIEND, OF HANNIBAL, MISSOURI.

METHOD OF TREATING WHEAT.

1,136,597.

Specification of Letters Patent. Patented Apr. 20, 1915.

Application filed June 29, 1914. Serial No. 847,934.

To all whom it may concern:

Be it known that we, ORLANDO M. FRIEND and SAMUEL E. FRIEND, citizens of the United States, residing in Hannibal, in the county of Marion and State of Missouri, have invented new and useful Improvements in Methods of Treating Wheat, of which the following is a specification.

Our invention relates to a novel method of treating wheat, to prepare the same for grinding, according to which, in a continuous operation, the wheat is washed, tempered, heated and hulled.

Prior to our invention, machines, or apparatus, have been used for washing, hulling, (i. e. removing the outer coating or beewing), tempering and heating the wheat, but so far as we are aware, these operations have been carried out separately, and by the use of separate apparatus in each case. Thus, in the ordinary practice of milling wheat, the wheat is cleaned by the use of wheat cleaning machines; it is then washed and placed in bins or tanks, where it is allowed to temper; and finally, if the weather is very cold, or the wheat be frosted, it may be heated.

By means of our invention, the operations of washing, tempering or moistening, heating and hulling wheat are, or may be, performed in a continuous operation, and by the use of a single machine, no larger than an ordinary wheat cleaning machine, thereby effecting a great economy, both in time and in cost of apparatus. Furthermore, we have found that in the treatment of wheat, according to this method, it is not only effectively and rapidly tempered or moistened and, if desired, heated, but it is more thoroughly cleaned and hulled than by any other system or method of treatment known to us.

In order that the practice of our method may be thoroughly understood, we have illustrated in the accompanying drawing, the machine now used by us for practising it; this machine, however, forms no part of the present invention, but forms the subject matter of a separate application for patent.

In the accompanying drawing:—Figure 1 is a view partly in longitudinal section and partly in elevation, showing a machine embodying our invention; Fig. 2 is a cross sectional view thereof, on the lines 2—2 and

2^a—2^a of Fig. 1; Fig. 3 is a cross section on the line 3—3 of Fig. 1; Fig. 4 is a view in elevation of one of the agitator arms; and Fig. 5 is a fragmentary view of the end portion of one of the agitator arms.

Referring now to these drawings, the numeral 1 indicates the casing of the machine, which in practice is about four feet in length, the bottom portion being semicircular in cross section, and having perpendicular side members 2 which support a top or cover 3, preferably made in two parts, as shown.

The numerals 4 indicate the ends of the casing, to each of which is secured a casting 5 affording a bearing 6 and a standard 7, on which the machine is supported. The ends 4 are centrally apertured concentrically with the bottom portion of the casing, and projecting through these apertures, and into the bearing 6 is a shaft 8 which extends longitudinally through the casing. Fixedly secured at the center of this shaft is a force feed device in the form of a double auger 9, which is concentric with the semicircular bottom portion, and is adapted to rotate at a distance of about one-half an inch therefrom. Mounted on the side walls 2 is a partition 10 which is provided with a semicircular recess to surround the auger, so as to provide, with the bottom portion of the casing, a circular space in which said auger rotates, and which, with said auger, serves to divide the casing into two chambers, one of which, at the right of the auger, as shown in Fig. 1, and indicated by the numeral 11, we term the agitating chamber, and the other of which, to the left of the auger, and indicated by the numeral 12, we term the hulling chamber.

Mounted on the shaft 8 in the chamber 11 are a series of S-shaped agitators 13, which are arranged from right to left in a progressively advanced relation to each other about the shaft, and are designed to be rotated with their convex side foremost. Similarly mounted on the shaft 8 in the chamber 12 are a series of agitators 14 which are similar in all respects to the agitators 13. Both sets of agitators have their outer or convex face forwardly inclined, that is, inclined toward the left-hand end of the machine, as indicated more clearly at 15 in Fig. 5, so as to impart a slight forward

movement to the grain as it is agitated. In addition, the outer portion of each convex face of the agitators is provided with a series of transverse ribs 16 to provide a more severe frictional action on, or rubbing of, the grain, than occurs with a perfectly smooth surface, as contemplated in our prior machine referred to.

The top 3 of the casing is provided near 10 one end with an opening 17, which is surrounded by a vertically-disposed housing 18, secured to the top of, and communicating with which is a longitudinally-disposed housing 19. Extending through the housing 18, and pivotally mounted in the side walls thereof, is a rock shaft 20 to which is fixedly secured at its upper end, a swinging valve 21, the free end of which moves in proximity to the wall of the casing 18. The rock shaft 20 has an arm 22 formed integral with, or fixedly secured to one end thereof, and projecting rearwardly therefrom, slidably and adjustably mounted on which is a weight 23. By adjusting this weight on the arm 22, 25 the weight of grain necessary to maintain the valve 21 in an open position may be varied, thus tending to regulate the feed of the grain, while the valve will tend to automatically close as the maximum flow of 30 grain permitted by the adjustment decreases. This automatic action of the valve, in conjunction with the spring hereinafter referred to, is utilized in controlling the admission of water and of steam to the grain 35 through the mechanism now to be described.

Mounted on the cover 3, and extending therethrough to communicate with the interior of the casing, is a pipe 24, which is provided with a cup 25.

40 The numeral 26 indicates a water pipe communicating with any suitable source of supply and having a depending end portion 27 terminating above the cup 25, and provided with a valve 28 which may be turned 45 to various positions to regulate the maximum amount of water which may pass into the cup 25, and thence into the casing. By having the water flow into the cup 25 in the manner described, the attendant is able to 50 ascertain by observation whether the water is running, and also, in a general way, the amount of water being supplied to the wheat.

55 The numeral 29 indicates a steam pipe communicating with any suitable source of supply, and having a vertically-disposed portion 30 provided with a valve casing 31 in which is mounted a valve 32. Connected with the pipe 30 is a horizontal extension 33 60 provided with a hand valve 23, and having an end portion 35 which communicates with the interior of the casing 1 in the chamber 11 at a point considerably nearer the center of the casing 1 than the point at which the 65 water pipe 24 enters said casing. The water

pipe 27 is also provided with a valve casing 36 in which is mounted a valve, (not shown) and which is preferably of the type known as a gate valve. Secured to one end of the stem 37 of this valve is an arm 38, 70 the outer end of which is pivotally connected to one end of a link 39, the opposite end of which is pivotally connected to one end of a lever 40, which is pivotally mounted at 41 intermediate its ends on the side 75 wall of the casing 18. The lower end of the lever 40 is provided with a series of apertures 42 in one or the other of which is connected, by a suitable pin, one end of a connecting rod 43, the opposite end of which is 80 provided with a series of apertures 44, in one or the other of which is connected, by a suitable pin, the outer end of a crank arm 45, the opposite end of which is connected to one end of the rock shaft 20. A coil spring 85 46 is connected at opposite ends to the lever 40 and crank arm 45 near their upper and lower ends, respectively. Pivotally connected to the lever 40 between the pivot 41 and its outer end is one end of a link 47, the 90 opposite end of which is connected to the outer end of a crank arm 48, the lower end of which is connected to the stem of the valve 32.

From the construction described, it will 95 be seen that as the valve 21 is moved downward by the weight of the grain, such movement, through the lever mechanism above described, will open the valves of the water and steam pipes, and as the flow of 100 grain ceases, and the valve 21 rises, the opposite movement of these parts occasioned thereby, will close these valves and stop the flow of water and steam. It is desirable to start and stop the flow of water practically 105 co-incident with the flow or cessation of flow of the grain, and this we attain by having the connecting rod operating the crank arm of the water valve connected to the outer end of the lever 40, which, of course, 110 has a greater arc of movement and moves faster than any part of the lever nearer the pivot 41. The rapidity with which the valves are closed in the operation of the device can be regulated by connecting the end 115 of the rod 43 to the lever 40 nearer to or farther from the lower end thereof, as will be readily understood. The spring 46 acts with the weight 23 in tending to close the valve 21, and further acts to prevent the valve 21 from constantly vibrating or rocking up and down, as frequently occurs when only the weight 23 is employed, the spring exerting a uniform tension, while the resistance of the weight decreases as the valve 120 opens wider and increases as the valve moves upward.

Extending through the horizontal casing 19 and journaled in bearings 49 at opposite ends thereof is a shaft 50 on which is mount-

ed within the casing 19 a worm conveyer 51. The upper side of the casing is provided with an opening 52 to which will be connected a spout, trough, or other suitable conveying means for feeding the wheat into the casing 19. The lower side of the casing 19 is provided near one end with an outlet opening 53 which communicates with the casing 18 through the top thereof, as shown in Fig. 2. The outer end of the shaft 50 is provided with a sprocket wheel 54, and a similar sprocket wheel 55 is mounted on a projecting end of the shaft 8, and over these sprocket wheels is passed a sprocket chain 56. The shaft 8 has also secured to its opposite end a pulley 57 by means of which it is rotated through the medium of a belt (not shown). The chamber 12 is provided in one of its vertical side walls with a discharge opening 58 which is normally closed by means of a door 59 hinged at its upper end to the casing 1, as indicated at 60, and provided toward its lower end with an arm 61 on which is adjustably mounted a weight 62, which latter offers a certain amount of resistance to the opening of the door 59, to permit the discharge of grain from the chamber 12 so that the grain is always maintained under pressure.

The casing 19, with its worm conveyer 51, provides a feed control device, enabling us to stop the flow of grain simultaneously and automatically with the stopping of rotation of the shaft 8, and then the worm conveyer not only ceases to force the grain into the casing 18, but it acts as a closure to the opening 53, to prevent the flow of the grain by gravity into said casing.

In practising our invention, the wheat, being fed into the chamber 11 in loose bulk, said chamber is simultaneously supplied with the requisite amount of water to temper the wheat, while at the same time the wheat is subjected to continuous agitation, due to the action of arms 13, this treatment serving to insure that the moisture shall reach, or be distributed thoroughly through and over all of the grain, while the frictional contact of the arms with the wheat, though relatively gentle, is sufficient to loosen up the outer coating. The combined action of the water and agitation will, at the same time result in the thorough washing of the grain. In order to facilitate the more ready access of the moisture to the interior of the grain, and at the same time to hull the grain, the wheat is next forced, by auger 9, into the chamber 12, where, due to the construction described, it is maintained under a regulated pressure, while subjected to agitation and frictional contact with the arms 14, and at the same time the grains are forced to rub against each other, the net result being the thorough removal from the grain of all adhering dirt, as well as the outer hull

particles, which have been previously loosened by treatment in chamber 11. Wheat in its natural condition, does not readily absorb moisture, such action being, to a large extent, prevented by the outer hull. By the removal of this hull, as above described, the grain is in a condition to readily absorb moisture, and such absorption occurs in the chamber 12 more readily and with greater uniformity than with any other system of tempering or moistening wheat known to us. It will be understood that by first loosening the outer hull, by the combined action of moisture and agitation in chamber 11, we place the wheat in condition not only to have the outer hull readily removed by the frictional action to which it is subjected in chamber 12, but as the moisture has been thoroughly disseminated throughout the whole body of the grain, each kernel of grain is in condition to at once absorb moisture as its outer hull particles are removed to expose the more absorbent part of the grain covered by the hull. Simultaneously with the inflow of water to the chamber 11, steam may be admitted through the pipe 35, to heat the grain, and this heating by producing a slight expansion of the grain, and thereby opening the pores thereof, likewise facilitates entrance of moisture to the grain. The heating of the wheat may be to any desired degree, the temperature being regulated by the amount of steam supplied to the chamber 11, and such heating having the same beneficial effect, when conditions call for its use, as the heating of wheat as now practised.

We desire to emphasize the advantage and economy in heating the wheat according to the present method. In the dry heating of wheat, as now commonly practised, a very considerable amount of moisture is expelled from the wheat, and although the wheat may be subsequently thoroughly washed and moistened, this loss of moisture can never be totally restored. There is always therefore, what is known as an "invisible loss" in the employment of such system of heating wheat.

According to our invention wet steam is supplied to the grain, while the grain itself is moist, with the result that not only is the wheat heated, but this is accomplished with an actual gain in moisture in the wheat, instead of a loss.

After the wheat passes through our machine, it is conveyed to tempering tanks of the usual construction, and is then passed through cleaning machines, such as are commonly employed in mills, in which the husk, dirt and germ removed from the grain, in our machine, are separated therefrom by suction. In practice we run the wheat from the tempering tanks through a second ma-

- chine, of our construction, but without the use of water or steam, in which the wheat will be thoroughly polished. It is then cleaned, as described.
- 5 In actual operation, we have found that wheat treated according to our invention, will have the outer husk and adhering dirt, including whiskers and smut, thoroughly removed therefrom, and after this refuse matter has been separated from the wheat in the well-known way, the latter will be in an ideal condition for the subsequent milling operation.

By referring in the specification and claims to agitating the grain "in bulk" or "in loose bulk," we refer to acting upon the body of grain in mass, so that, in the agitation of the grain not only is the grain continuously subjected to mechanical rubbing by the passage of the agitator arms through the mass of grain, but the grains themselves are caused to rub against each other.

We claim,

1. The method of treating wheat, which consists in subjecting the same, in bulk, to the concurrent action of moisture and frictional agitation and continuously decorticating the wheat thus treated.

2. The method of treating wheat, which consists in subjecting the same, in bulk, to the concurrent action of moisture and attrition and continuously decorticating the wheat thus treated.

3. The herein described method, which consists in frictionally agitating heated moistened wheat and continuously decorticating the wheat thus treated.

4. The herein described method, which consists in frictionally agitating in bulk moistened wheat, and simultaneously heating the same and thereupon, and in a continuous operation, decorticating the wheat thus treated.

5. The method of treating wheat, which consists in subjecting the same in bulk, to the concurrent actions of frictional agitation, moisture and heat and thereupon, and in a continuous operation, decorticating the wheat thus treated.

50 6. The method of treating wheat, which consists in subjecting the same in bulk, in a closed receptacle, to the concurrent actions of frictional agitation, moisture and steam and thereupon, and in a continuous operation, decorticating the wheat thus treated.

7. The method of treating wheat, which consists in frictionally agitating the same in loose bulk while supplying water thereto, and continuously forcing the wheat thus

treated into a closed chamber, and therein frictionally agitating the same, while maintaining it under pressure.

8. The method of treating wheat which consists in agitating the same in loose bulk in a closed chamber, and simultaneously admitting water and steam to said chamber, and continuously forcing the wheat thus treated into a second chamber, and therein further frictionally agitating the same, while maintaining the wheat under pressure.

9. The method of treating wheat, which consists in frictionally agitating the wheat in loose bulk and simultaneously supplying water thereto, for the purpose of washing and moistening the grain, and then subjecting the wheat in bulk, under pressure to further frictional agitation, to clean the wheat.

10. The method of treating wheat, which consists in frictionally agitating the wheat in loose bulk and simultaneously admitting water and steam thereto, for the purpose of washing, tempering and heating the wheat, and subsequently in a continuous operation frictionally agitating the wheat in bulk, under pressure, to clean it.

11. The method of treating wheat, which consists in subjecting the wheat in loose bulk to the action of mechanical agitators while supplying water thereto, and then in a continuous operation subjecting the wheat, in bulk and under pressure, to the further action of mechanical agitators.

12. The method of treating wheat, which consists in acting on the grain in loose bulk to loosen the outer fibrous coating thereof, while at the same time supplying moisture and heat thereto, and continuously decorticating the grain thus treated.

13. The method of treating wheat which consists in subjecting heated moistened wheat in bulk to pressure and attrition.

14. The method of treating wheat which consists in moistening wheat in bulk and at the same time mechanically loosening the outer fibrous coating thereof, and then continuously subjecting the wheat thus treated and in bulk to the action of pressure and attrition.

In testimony whereof, we have hereunto set our hands in presence of two subscribing witnesses.
